CLAIM

The ornamental design for an emergency vehicle light-bar, as shown.

DESCRIPTION

FIG. 1 is a perspective view of an emergency vehicle light-bar showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment emergency vehicle light-bar thereof;

FIG. 9 is a front view of the housing of the light-bar thereof;

FIG. 10 is a back view of the housing of the light-bar thereof;

FIG. 11 is a right side view of the housing of the light-bar thereof;

FIG. 12 is a left side view of the housing of the light-bar thereof;

FIG. 13 is a top view of the housing of the light-bar thereof; and,

FIG. 14 is a bottom view of the housing of the light-bar thereof.

The broken lines depict unclaimed environmental subject matter.
